UNITED STATES PATENT OFFICE

106,140

DESIGN OF A GLOVE

George U. Larom, Brightwaters, N. Y.

Application August 17, 1937, Serial No. 71,151

Term of patent 3½ years

To all whom it may concern:

Be it known that I, George U. Larom, a citizen of the United States, residing at Brightwaters, county of Suffolk, and State of New York, have invented a new, original, and ornamental Design of a Glove, of which the following is a specification, reference being had to the accompanying drawing, forming a part thereof.

Figure 1 is a view of the obverse side of the glove embodying my new design showing it as applied to a human hand.

Figure 2 is a view of the reverse side thereof.

Figure 3 is an enlarged detailed view of the finger tip thereof applied to a finger.

The characteristic feature of the design consists in a fanciful weave adjacent the finger tip on the obverse side of the glove substantially covering the fingernail portion of a hand when the glove is worn.

The cross hatching in Figures 1 and 2 serves to indicate the mesh fabric which is shown in detail in Figure 3.

I claim:

The ornamental design of a glove as shown and described.

GEORGE U. LAROM,
